(57) **CLAIM**

The ornamental design for an ice bag, as shown and described.

DESCRIPTION

FIG. 1 is a left, front perspective view of an ice bag showing my new design.

FIG. 2 is a right front perspective view of the ice bag of FIG. 1;

FIG. 3 is a front perspective view of the ice bag of FIG. 1; FIG. 4 is a rear perspective view of the ice bag of FIG. 1; FIG. 5 is a left side perspective view of the ice bag of FIG. 1;

FIG. 6 is a right side perspective view of the ice bag of FIG. 1;

FIG. 7 is a top perspective view of the ice bag of FIG. 1; FIG. 8 is a bottom perspective view of the ice bag of FIG. 1; and,

FIG. 9 is a top front perspective view of the ice bag of FIG. 1.

The broken dash lines shown in the drawings illustrate stitching patterns and are not to be considered disclaimers of scope, in the one illustrated embodiment.
